C. D. BONSALL

CAR ROOF

Filed Dec. 2, 1921

Fig. 1.

Patented June 12, 1923.

1,458,385

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed December 2, 1921. Serial No. 519,305.

To all whom it may concern:

Be it known that I, CHARLES DAVID BONSALL, a citizen of the United States, and a resident of the city of Pittsburgh, in the 5 county of Allegheny and State of Pennsylvania, have invented a certain new and useful Improvement in Car Roofs, of which the following is a specification.

The invention relates to flexible outside 10 metal car roofs of the general type shown in C. C. Murphy Patent, No. 1,133,493, dated March 20, 1915, wherein the roof sheets are pivoted near their ridge ends to the roof sheathing and are connected along their side 15 and ridge margins by flexible seams; and it relates particularly to the ridge construction of roofs of this type. In roofs of this type, the roof sheets are arranged in pairs on opposite sides of the ridge and, heretofore, the 20 two sheets of each pair have been pivoted to the roof substructure by means of ridge anchor saddles, which are pivotally secured to the ridge of the car and have raised pivot bosses that fit within similar raised pivot 25 bosses formed in the roof sheets near their ridge ends. In such earlier constructions, the roof sheet bosses are held down on the anchor saddle bosses by means of extra running board saddles whose under sides are 30 recessed to receive the roof sheet bosses, whereby said roof sheets are free to pivot or slue on the roof substructure, but are held from slipping off the eaves. The principal objects of the present invention are 35 to pivotally secure the roof sheets in place without the use of the bossed ridge anchor saddles and without the use of the extra running board saddles and thereby save the cost thereof; to eliminate the bossing of the 40 roof sheets and thereby save the cost of the bossing operation; and to locate the pivotal securing means outside of the sheets and entirely within the ridge covers.

The invention consists principally in an 45 anchor member for holding the sheets down on the car and for preventing bodily movement thereof crosswise of the car, said member also functioning as a pivot for the roof sheets to turn on in accommodating 50 themselves to the various distortions of the car substructure; and the invention further consists in the arrangements and combinations of parts hereinafter more fully described and claimed.

In the accompanying drawing, which 55 forms part of this specification and wherein like reference numerals refer to like parts wherever they occur.

Fig. 1 is a plan view of a portion of a car 60 roof provided with a pivot anchor member embodying my invention, parts being broken away to more clearly illustrate the invention;

Fig. 2 is an enlarged transverse cross-section through the ridge portion of the car 65 roof, the section being taken through one of the pivot anchor members on the line 2—2 in Fig. 1;

Fig. 3 is a fragmentary plan view of the 70 ridge portion of the roof, in the region of one of the pivot anchor members, the ridge seam cap being broken away to disclose the anchor member;

Fig. 4 is a transverse cross-section similar to Fig. 2, the pivot anchor member being 75 shown in end elevation; and

Fig. 5 is an end elevation of a detached pivot anchor member.

The roof illustrated in the accompanying drawing comprises roof sheathing boards 6, 80 supporting at the eaves by side plates 7, and at the ridge by a ridge pole 8. Metal roof sheets 9 are arranged in pairs on opposite sides of the ridge, the two sheets of a pair being disposed end to end crosswise of the 85 car and spaced apart from each other on opposite sides of the ridge and from adjacent pairs along their side margins. Mullions or battens 10 are secured to the roof sheathing between the side margins of the 90 sheets, and are of less width than the space between the side margins of the sheets. The roof sheets are held down on the car at the eaves by means of flashing strips 11, which are secured to the side plates and have 95 doubled-back portions 12 adapted to interlock with the doubled-under eaves portions of the roof sheets.

The side margins of adjacent roof sheets, together with the mullions located therebetween, are covered by channel-shaped transverse seam covers 13 whose side walls interlock with the side seam flanges 14 of the roof sheets. The transverse seam covers 13 extend from ridge to eaves, and are held down at the eaves by turning their eaves ends under the doubled-back portions 12 of the flashing eaves strips 11, or in any other de-

sirable manner. The ridge ends of the transverse seam covers 13 are secured to the car by means of four-way ridge corner caps 15.

5 The roof sheets are provided at their ridge ends with raised rebent flanges, which form hollow ribs 16. The spaced ridge ribs 16 are straddled by channel-shaped ridge seam covers 18, whose adjacent ends are covered by the ridge corner caps 15 and are held in 10 proper alignment thereby. The corner caps 15 are secured to the substructure by means of bolts 19, which also secure the running board saddles 20 in position. Running boards 21 are secured to the running board 15 saddles 20, which rest on the transverse seam covers 13, and are supported by the mullions 10, thus permitting movement of the roof sheets under the ridge and transverse seam covers.

20 The ridge ends of each pair of oppositely disposed roof sheets are held down on the roof substructure by means of a sheet metal pivot anchor member 22, which also serves to space the sheets apart at the ridge and 25 to prevent bodily movement of said sheets crosswise of the car. The anchor members 22 are located between the ridge ends of each pair of oppositely arranged roof sheets midway between their side margins and are 30 secured in place by bolts 23, which extend through the roof sheathing and ridge pole. Each anchor member 22 comprises a flat body portion, whose side margins are provided with raised rebent flanges that form 35 hollow ribs 24 which overlap and embrace the spaced ridge ribs 16 of oppositely arranged sheets.

The hollow ribs 24 of the anchor members or clips 22 form downwardly opening 40 grooves or channels 17 on opposite sides of the clips. The side walls of each rib 24 of an anchor member are curved in opposite directions away from each other (that is from the middle towards each end), thus 45 forming opposing convex surfaces in walls of the grooves or channels 17 formed by the said hollow ribs, whereby the distance between the opposing side walls of each downwardly opening groove is a minimum 50 midway of the length of the grooves and increases gradually toward each end thereof. The width of the grooves 17 midway of their length corresponds to the width of the ridge ribs 16, whereby the grooves 55 snugly embrace said ribs at the middle of the ridge ends of the sheets and thus maintain a proper spacing of the ridge ends of the sheets and prevent bodily movement of said sheets crosswise of the car.

60 By reason of the double convexity of the grooves 17 of the anchor member, each side of a groove 17 contacts with the adjacent side of a roof sheet rib 16 along one line only, with the result that each roof sheet of 65 an oppositely arranged pair has pivotal

tangential contact with both walls of a groove of said anchor member, whereby said roof sheets are permitted to slue or oscillate about the engaging or contacting portions of the anchor members in response to 70 the weaving of the car frame.

The principal advantages of the arrangement described is that it eliminates the extra running board saddles, the bossed anchor saddles and wholly eliminates the need for 75 the expensive operation of bossing the roof sheets.

The invention is not restricted to the precise forms and arrangements shown and described.

80 What I claim is:—

1. A flexible car roof comprising roof sheets spaced apart along their adjacent margins and having hollow ribs extending lengthwise thereof, and an anchor member secured to the car between the spaced margins of adjacent sheets, said anchor member engaging both walls of the rib of each of said adjacent sheets, thereby preventing bodily movement thereof towards and away from each other, and having tangential contact with said walls, thereby permitting said sheets to slue about the contacting portions of said anchor member in response to the weaving of the car frame.

90 2. A flexible car roof comprising roof sheets spaced apart along their adjacent margins and having hollow ribs formed in their adjacent margins, a seam cover straddling the ribs of adjacent sheets, and an anchor member located within said seam cover and secured to the car between the spaced margins of adjacent sheets, said anchor member engaging both walls of the ribs of adjacent sheets to prevent bodily movement thereof towards and away from each other, the surfaces of said member that engage both walls of the rib of a sheet being curved in opposite directions, whereby said anchor member has tangential contact with 100 each wall of a rib, thereby permitting said sheets to slue about the contacting portions of the anchor member.

110 3. A flexible car roof comprising roof sheets oppositely arranged on each side of the ridge and having raised rebent flanges at their ridge ends, a seam cover straddling the ridge flanges of oppositely arranged sheets, and an anchor member located beneath said ridge cap and secured to the car between the middle of the ridge ends of said oppositely arranged sheets, said anchor member having oppositely curved surfaces that engage the middle portions of both 115 walls of the ridge flanges of oppositely arranged sheets to prevent bodily movement thereof crosswise of the car and to permit sluing of said sheets about the contacting portions of the reversely curved surfaces 120 of said anchor member.

4. A flexible car roof comprising roof sheets spaced apart along their adjacent margins, and an anchor member secured to the car between the spaced margins of adjacent sheets, the adjacent margins of said sheets and said anchor member being formed with cooperating rib and groove portions respectively that extend lengthwise of said margins and prevent bodily movement 10 of the sheets towards and away from each other, the side walls of each pair of said cooperating rib and groove portions having tangential contact with each other, thereby permitting the sheets to slue in response to 15 the weaving of the car frame.
5. A flexible car roof comprising roof sheets spaced apart along their adjacent margins, and an anchor member secured to the roof between adjacent sheets, the adjacent margins of said sheets and said anchor members being each formed with raised rebent flanges, the adjacent marginal flanges of said sheets and said anchor member being overlapped, the side walls of each pair of 20 lapped flanges of said sheets and said anchor member having tangential contact with each other, thereby preventing bodily movement of adjacent sheets towards and away from each other and permitting sluing of the 25 sheets in response to the weaving of the car frame.
6. A flexible car roof comprising roof sheets oppositely arranged on each side of the ridge, an anchor member secured to the roof between the spaced ridge ends of said 30 oppositely arranged sheets, the adjacent side margins of said sheets and said anchor member being formed with lapped hollow ribs adapted to prevent bodily movement 35 of the sheets cross-wise of the car, and seam covers spanning the lapped hollow ribs of said sheets and said anchor member, the side walls of one rib of a lapped pair being reversely curved lengthwise thereof, whereby 40 the reversely curved side walls of one rib of a pair have tangential contact with the side walls of the other rib of said pair, thereby permitting the sheets to slue in response to the weaving of the car frame.
7. A flexible car roof comprising roof sheets spaced apart along their adjacent margins which are formed with raised ribs, and an anchor member secured to the car between the spaced margins of adjacent 45 sheets and having hollow raised ribs that extend lengthwise of said margins and lap the raised marginal ribs of adjacent sheets, the side walls of the ribs of the anchor member having tangential contact with the side 50 walls of the marginal ribs of the sheets.
8. A flexible car roof comprising roof sheets oppositely arranged on each side of the ridge and having raised rebent flanges at their ridge ends, a seam cover spanning the ridge ends of oppositely arranged sheets, and an anchor member secured to the car between the spaced ridge ends of oppositely arranged sheets and having raised rebent flanges adapted to fit over the ridge flanges of oppositely arranged sheets to hold the 70 sheet down on the car and to prevent bodily movement of said sheets crosswise thereof, the side walls of the flanges of said anchor member having tangential contact with the side walls of the ridge flanges, thereby permitting the sheets to slue about the contacting portions of the anchor member flanges in response to distortions of the car frame. 75
9. A flexible car roof comprising roof sheets oppositely arranged on each side of the ridge and having raised rebent flanges at their ridge ends, and an anchor member secured to the car between the spaced ridge ends of oppositely arranged sheets and having raised rebent flanges adapted to fit over the ridge flanges of oppositely arranged sheets, the side walls of the anchor member flanges being reversely curved from end to end whereby the sides of the anchor member flanges have tangential contact with the 80 sides of the roof sheet flanges. 85
10. A flexible car roof comprising roof sheets oppositely arranged on each side of the ridge and having raised ribs at their ridge ends, an anchor member secured to the car between the ridge ends of said sheets, said anchor member having downwardly opening grooves formed therein adapted to straddle the ribs of oppositely arranged sheets, said grooves being wider at the ends than at the middle, thereby permitting a limited angular movement of said ridge ribs in said grooves. 90
11. A flexible car roof comprising roof sheets oppositely arranged on each side of the ridge and having raised ribs at their ridge ends, a seam cover straddling the ridge ribs of oppositely arranged sheets, and an anchor member located within said cap and secured to the car roof between the spaced ridge ribs of said oppositely arranged sheets, said anchor member being formed with downwardly opening grooves which straddle the ridge ribs of oppositely arranged sheets, the walls of said 100 grooves being reversely curved from end to end thereof forming convex surfaces that have tangential contact with the ridge ribs located therein. 110
12. As an article of manufacture, an anchor member for ribbed car roof sheets, said anchor member having longitudinally extending oppositely curved surfaces adapted for tangential engagement with both side walls of the rib of a roof sheet to prevent 115 bodily movement of said sheet and to permit sluing thereof. 120
13. As an article of manufacture, an anchor member for a pair of oppositely arranged car roof sheets whose adjacent mar- 125 130

gins are provided with ribs, said anchor member being adapted to be secured to the car between the ribs of said oppositely arranged sheets and having longitudinally extending grooves formed therein adapted to embrace a rib of a sheet, the side walls of said grooves being convex to permit a limited angular movement of the ribs therein.

16 14. As an article of manufacture, an anchor clip for a pair of oppositely arranged

car roof sheets whose adjacent margins are formed with upstanding hollow ribs, said clip having upstanding hollow ribs formed therein adapted to straddle the ribs of the 15 roof sheets, each rib of said clip having reversely curved side walls forming reverse convex surfaces adapted to contact tangentially with the side walls of a roof sheet rib.

Signed at Parnassus, Pa. this 28th day 20 of November, 1921.

CHARLES DAVID BONSALL.
